Herbert R. Miller INVENTOR

by Taylor & Ulmer
ATTORNEYS.

UNITED STATES PATENT OFFICE.

HERBERT R. MILLER, OF FORT WAYNE, INDIANA.

GARBAGE-RECEPTACLE.

1,245,256.

Specification of Letters Patent.

Patented Nov. 6, 1917.

Application filed February 21, 1916. Serial No. 79,552.

To all whom it may concern:

Be it known that I, HERBERT R. MILLER, a citizen of the United States, residing at Fort Wayne, in the county of Allen and State of Indiana, have invented new and useful Improvements in Garbage-Receptacles, of which the following is a specification.

The invention relates to garbage receptacles. Sanitary restrictions in most communities require garbage to be deposited in receptacles from which it is collected at intervals of time. Metallic receptacles are generally used for the purpose. Formerly the garbage was deposited in the can without draining it so that the collector was unnecessarily inconvenienced in removing it especially in freezing weather. At the present time in many communities the residents are required to wrap all garbage in paper before depositing it in the receptacle. The wrapping of the garbage in paper of the kind usually to be found in most homes requires that the garbage shall be first drained in order that the wrapper shall remain intact. The draining and wrapping of the garbage increases the labor of the housewife and is objectionable.

The object of my invention is to provide a cheap receptacle into which garbage as collected in the home may be deposited and drained and which when filled, or at any time before it is fully filled may be deposited in the garbage can or otherwise disposed of along with its contents.

The invention consists in a perforated paper receptacle with means by which it is supported while in use.

In the accompanying drawings I illustrate how the invention may be carried out in practice, in which

Figure 1 is a perspective view of the container and support ready for use; Fig. 2 a perspective view of the container; Fig. 3 a perspective view of the support; Fig. 4 a plan view of a modified support; Fig. 5 an elevational view of the same and Fig. 6 a modified form of the post.

Referring to the drawings the receptacle 10 is formed preferably of a single sheet of non-metallic material as paper of suitable weight, and having preferably a substantially square or oblong bottom 11 which is produced by folding the sheet as is commonly done in the manufacture of bags. Apertures 12 are provided in bottom 11

adjacent the four corners and any desirable number of apertures 13 are provided in the several sides. In practice the bottom will be folded up on one side, as 14, of the receptacle and sides 15 are folded inwardly on lines 16^a. A gang punch arranged to produce apertures 12 in bottom 11 is then applied to the folded receptacle and driven through it. This one operation will produce 65 apertures 12 and all of the apertures 13, except apertures 13^a which are punched separately.

The above method of producing the apertures is most economical, but any method 70 may be pursued which will provide apertures 12, and a suitable number of apertures 13.

The support consists of a slotted base 16 having four vertical posts 17 secured adjacent its four corners respectively, and corresponding in distances apart to the distances between apertures 12. The posts may be carried through base 16 to provide legs 18, or the base may be provided with suitable 80 legs and sockets 19 (Fig. 4) into which sockets posts 20 may be inserted.

The receptacle is placed on the support by inserting the upper ends of posts 17 into apertures 12 and then drawing the receptacle toward base 16 until bottom 11 abuts the base. Posts 17 will extend upwardly within the receptacle and engage the same to prevent its collapse and maintain its mouth in open position. Where sockets 19 90 and posts 20 are used the receptacle is placed on the base with the sockets extending up through apertures 12; then the posts are inserted in the sockets. I prefer the former

construction of support as it is less laborious 95 to install a receptacle upon it than on the latter construction. In both constructions the posts may be connected at their upper ends as shown in Fig. 5 and the cross-members 22 may be serrated, the projection 23 100 being sharpened for engagement by the mouth of the receptacle. The receptacle in this instance will be of a size to lie within the posts and be supported at its mouth as just described.

The posts 17 instead of being secured to base 16 may be slidable therein, one end of each post having a shoulder 24 secured thereto, the opposite end being enlarged to provide shoulder 25. To install the receptacle the base is elevated on the posts until it abuts shoulder 25. The short ends

of the posts beyond the shoulders are inserted through apertures 12 and the base and receptacle are lowered on the posts until the base abuts shoulder 24.

5 By any of the arrangements above described the receptacle is supported until its removal is desired, whereupon it is disposed of with its contents with very little expenditure of energy and at very small cost.

10 What I claim is:

1. A garbage receptacle consisting of a paper container having an open mouth and a plurality of apertures in its bottom and supporting means for said container including upright members extending through its bottom and upwardly in contact with the inner surface of its walls as and for the purposes described.

2. A garbage receptacle consisting of a container formed of fibrous material and having an open mouth and a plurality of apertures in its bottom and supporting

means for said container, including upright members, with portions of the support projecting upwardly through said apertures 25 into the container for maintaining the mouth thereof in open position as well as the walls thereof in required garbage receiving position.

3. A garbage receptacle consisting of a 30 container having an open mouth and a plurality of apertures in its sides and bottom and supporting means for said container, including upright members, the said apertures being adapted to provide drainage for the 35 interior of the container, a portion of said apertures in the bottom being adapted to receive said upright supporting members for maintaining the mouth of the container in open position.

40 In witness whereof I hereunto set my hand this 15th day of February, 1916.

HERBERT R. MILLER.
